UNITED STATES PATENT OFFICE.

GEORGE J. COMINNOS, OF PITTSBURGH, PENNSYLVANIA.

FURNACE.

1,113,411.

Specification of Letters Patent. Patented Oct. 13, 1914.

Application filed April 8, 1914. Serial No. 830,377.

To all whom it may concern:

Be it known that I, GEORGE J. COMINNOS, a subject of the King of Greece, and residing in the city of Pittsburgh, in the county 5 of Allegheny and State of Pennsylvania, have invented or discovered new and useful Improvements in Furnaces, of which the following is a specification.

My invention consists of a new and improved hot-air heating furnace intended for 10 use with gaseous fuel.

The object in view is to provide an inexpensive yet durable furnace which will produce the maximum heating results with the 15 expenditure of a minimum of gas.

Generally speaking my furnace consists of an outer casing with a heater-body mounted therein, said heater-body comprising 20 a combustion chamber, having mounted therein an annular burner and communicating at its top with a horizontally extending annular fumes chamber from which the products of combustion escape to the chimney. An air flue extends up through the 25 axis of said burner and said combustion chamber into a cylindrical air-chamber formed within said annular fumes chamber and having one end opening into the interior of the casing while its other end receives 30 air from a fresh air pipe extending from without the casing. Flues extend from said air chamber through said fumes chamber to discharge the heated air into the upper part of the casing and mixing means are provided in said air chamber to thoroughly mingle the air admitted through the 35 fresh air pipe with the hot air rising through the axial flue. Means are also provided for baffling or retarding the products of combustion as they rise from the combustion chamber into the fumes chamber.

New and improved means are provided for controlling and regulating the admission of air into the combustion chamber to 45 obtain proper combustion.

The structure of the burner is such that the gas is expanded within the body of the burner before its admission to the perforated face thereof so that its pressure is increased and better flame jets insured.

Other novel features of construction and arrangement of parts will appear from the following description.

In the accompanying drawings, Figure 1 is an elevation, partially broken away and 55 in section, of my improved furnace; Fig. 2 is a view partly in section along the line II—II in Fig. 1 and also showing the outer wall of the combustion chamber broken away and the burner in elevation, and Fig. 60 3 is a section along the line III—III in Fig. 1.

The following is a detailed description of the drawings: A is the usual outer casing having means for admitting air at the bottom, such as pipe 1 and hot-air pipes 2 leading from the top. The heater, contained within the casing, is supported in any convenient manner, as for instance by means of the cross bar 3.

The structure of the heater is as follows: B is a cylindrical combustion chamber, open 70 at the top and having a central opening 4 in which is fixed the upwardly extending cylinder 5 down over which is slipped an outer sleeve 5^a of less height provided with a circumferential shoulder 6.

C is an annular burner slipped down over the cylinder 5 and resting on the shoulder 6, and having its outer wall provided with 75 the gas jet perforations 7.

8 represents a plurality of air ports in the bottom side wall of chamber B and 9 is an annular shutter mounted to rotate on said chamber and provided with holes 8^a which 80 may be brought into registration with the ports 8.

10 is a lever rigidly secured to the shutter 9 and extending out through a horizontal slot 11 in the casing A. It is evident that 90 by moving the shutter 9 by means of lever 10 the amount of air admitted to the combustion chamber may be nicely adjusted.

12 is the gas supply pipe leading from without the casing A up through the bottom of the chamber B into the burner C, the end of said pipe extending upwardly some distance into the burner. The discharge end of said pipe is between the inner wall of the 95 burner and an annular baffle 13 which extends in proximity to the outer wall of the burner from its top to a short distance of the bottom thereof. The burner is thus divided into two concentric chambers, into 100 the inner one of which the gas is received from the pipe 12 and wherein said gas is

heated and its pressure increased, and whence the expanded gas passes under the baffle 18 into the outer chamber whence it escapes through the perforations 7.

5 14 is an inclosed passage leading from the combustion chamber B to the outside of the casing A where it is closed by the door 15.

16 is the pilot light adjacent to the face of burner C whereby the latter may be 10 lighted when the gas is admitted to the burner.

D and E are outer and inner concentric drums mounted above the combustion chamber B in the following manner: The outer 15 drum D is provided on its lower side with an orifice provided with a depending neck 17 which rests upon the top of the combustion chamber B and is secured in place, as by the clamping ring 18. The inner drum 20 E is provided with a smaller orifice provided with a neck 19 extending downwardly within the neck 17 and slipping down within an annular flange 20 on the top of the burner C. It is evident that the air rising 25 up axially of the burner will discharge into the inner drum E while the products of combustion will rise up the neck 17, about the neck 19, into the outer drum D. One end of the inner drum is open to the interior 30 of the casing while its other end is connected with a fresh air pipe 22 leading in through the casing. 23 is a stationary mixing 35 worm in the drum E whose axis may be tube 24 with one open end. It is evident that the hot air rising into the drum through the axial flue is thoroughly intermingled with the fresh air entering through the pipe 22.

25 represents one or more flues leading 40 from the drum E, through the drum D, into the upper portion of the casing to convey the warm air from the drum E to the crown of the casing.

26 represents annular plates closing the 45 space between the inner and outer drums at their ends, thus forming an annular chamber for the reception of the products of combustion from the combustion chamber B.

27 is a spiral baffle in the neck 17 to retard 50 the passage of the fumes, said baffle being perforated as at 28, for the upper half of its upper convolution so that the fumes will escape evenly around the orifice in drum D.

55 29 is the fume pipe leading from the top of the drum D to without the casing and 30 is the horizontal check-draft pipe provided with a damper 31.

60 The pipe 1 extends horizontally through the furnace with its ends extending through the casing and screened. At its center it is provided with a vertical open neck 32 extending upwardly to a short distance below the lower end of the axial hot air flue. Along 65 its length said pipe is provided with open

ports 33 to admit air into the lower casing. Said pipe may if desired be connected to a fresh air supply tube.

34 represents dampers to regulate the admission of air into pipe 1.

When the furnace is in use the products of combustion ascend from the combustion chamber through the baffled neck 17 into the fumes drum D and passing over and around the walls of the air mixing drum E and 75 thence escape through the fume pipe 29 to the chimney. Air enters the pipe 1 and ascends about the heater within the casing to the crown thereof, becoming heated in its passage. Air also passes through the center 80 of the burner and the neck 19 into the air-mixing drum E where it mixes with the fresh air from the pipe 22 and the heated mixture escapes into the crown of the casing through the open end of the drum and 85 the flues 25.

It is evident from the foregoing that every advantage is taken of the heat of the products of combustion and the same are baffled and retarded in contact with the walls of the air passages and chambers to obtain the maximum heating effect. I am thus enabled to economize in the use of gas. No cast metal parts are required, the entire 95 furnace being made of sheet metal. There is thus no extra metal which must be heated and the cost of the furnace is much reduced.

What I desire to claim is:—

1. In a furnace, an outer casing; a combustion chamber mounted in the lower portion of said casing; an annular burner mounted in said combustion chamber; a horizontally placed annular fumes chamber mounted on said combustion chamber and communicating therewith through an open port, said fumes chamber having a fumes outlet to the exterior of the casing; a circular air-mixing chamber extending axially through said fumes chamber; flues extending through said fumes chamber and connecting said mixing chamber with the crown of the casing, and an air flue extending from the bottom of said casing axially of said burner and said combustion chamber into 115 said mixing chamber.

2. In a furnace, an outer casing; a combustion chamber mounted in the lower portion of said casing; an annular burner mounted in said combustion chamber; a horizontally placed annular fumes chamber mounted on said combustion chamber and communicating therewith through an open port, said fumes chamber having a fume outlet to the exterior of the casing; a 125 circular air-mixing chamber extending axially through said fumes chamber; flues extending through said fumes chamber and connecting said mixing chamber with the crown of said casing, and an air flue ex- 130

tending from the bottom of said casing axially of said burner and said combustion chamber into said mixing chamber, the interior diameter of said last named flue increasing above said burner.

3. In a furnace, an outer casing, a combustion chamber mounted in the lower portion of said casing; an annular burner mounted in said combustion chamber; a horizontally placed annular fumes chamber mounted on said combustion chamber and communicating therewith through an open port, said fumes chamber having a fumes outlet to the exterior of the casing; a circular air-mixing chamber extending axially through said fumes chamber; a fresh air connection for one end of said mixing chamber; flues extending through said fumes chamber and connecting said mixing chamber with the crown of the casing, and an air flue extending from the bottom of said casing axially of said burner and said combustion chamber into said mixing chamber.
4. In a furnace, an outer casing; a combustion chamber into said mixing chamber; an annular burner mounted in said combustion chamber; a horizontally placed annular fumes chamber mounted on said combustion chamber and communicating therewith through an open port, said fumes chamber having a fumes

outlet to the exterior of the casing; a circular air-mixing chamber extending axially through said fumes chamber, said mixing chamber being connected at its end to a 35 fresh air supply; flues extending through said fumes chamber and connecting said mixing chamber with the crown of the furnace; a mixing worm in said mixing chamber, and an air flue extending from the 40 bottom of said casing axially of said burner and said combustion chamber into said mixing chamber.

5. A heater comprising an annular combustion chamber; an air chamber within the same and concentric therewith; an annular burner mounted on top of said air chamber and forming the throat thereof; an annular fumes drum superimposed upon said combustion chamber and receiving the fumes therefrom through an open port, the open bore of said drum communicating with the throat of said air chamber; inclosed ducts through said drum communicating with said bore, and a fumes pipe leading from said fumes drum.

Signed at Pittsburgh, Penna. this 4th day of April, 1914.
